Term of patent 14 years

(Cl. D49—1)

FIG-1

FIG-2

FIG-3

FIG-4

FIG. 1 is a perspective view of a combined control panel and handle for a dishwashing machine showing our new design;

FIG. 2 is an end elevation thereof;

FIG. 3 is a front elevation thereof; and

FIG. 4 is a top plan view thereof.

The rear not shown is hollow.

The dominant features of our design reside in the portions shown in full lines, the broken line showing the dishwashing machine in FIG. 1 being for illustrative purposes only.

We claim:

The ornamental design for a combined control panel and handle for a dishwashing machine, as shown and described.
